UNITED STATES PATENT OFFICE.

WALTER D. DAVIES, OF BROOKLYN, NEW YORK, ASSIGNOR TO THE
ANSONIA CLOCK COMPANY, OF ANSONIA, CONNECTICUT.

DESIGN FOR A CLOCK-CASE FRONT.

SPECIFICATION forming part of Design No. 15,126, dated July 8, 1884.

Application filed March 14, 1884. Term of patent 7 years.

To all whom it may concern:

Be it known that I, WALTER D. DAVIES, of the city of Brooklyn, in the county of Kings and State of New York, have invented a new and original Design for a Clock-Front, of which the following is a specification, reference being had to the accompanying drawings, in which—

Figure 1 is a front view of a clock-front of my design, representing all the details of one half, but showing only the outline of the other half, which is an exact counterpart of that represented in detail. Fig. 2 is a profile view.

The front is composed of a frame, A, having an opening for the dial and a supporting-standard, B, for said frame, the profile being nearly flat, but the ornamentation being in relief.

The standard B is composed of two winged lions ²⁰ sejant and addorsed, and an interposed floriated column, b.

The general form of the frame A is elliptical. At each side are two pieces of scroll-work ornamentation, one of which, c d, extends from the column b nearly to the center of the side, and the other of which, e f, extends from a point near the middle of the side nearly to the top.

Between d and e, at the junction of the upper and lower scroll-work, is a foliated orna-

ment, g, and between the upper parts, f, of the upper scroll-work is a group of leaves and flowers, h i j k, which appear to run over the scroll-work, and from which there runs a string of flower-buds, l, reaching to the lower part e of the scroll-work.

Between the parts e and d there is on the outer margin a foliated and floriated ornamentation, m n.

What I claim, and desire to secure by Letters Patent, is—

1. In a clock-front, the design of the dial-frame, consisting of the scroll-work c d and e f, and the foliated and floriated ornaments g h i j k l m n, as herein shown and described. 45

2. In a clock-front, the design of the dial-frame and its supporting-standard, consisting of the scroll-work c d and e f, the foliated and floriated ornaments g h i j k l m n, and the winged lions sejant and addorsed, and the foliated and floriated column b, interposed between the said lions below the said scroll-work and foliated and floriated ornaments, all as herein shown and described. 50

WALTER D. DAVIES.
